UNITED STATES PATENT OFFICE.

GEORGE H. OLDRING, OF NEW YORK, N. Y.

GOLF TEE.

Application filed November 28, 1924. Serial No. 752,598.

Among the principal objects which the present invention has in view are: to provide means for teeing a golf ball without resorting to the usual method of erecting 5 a mound of sand or soil; to avoid loss of tees; to provide tees which will not interfere with the driving club used in the game; and to simplify and cheapen the construction of tees.

10

Drawings.

Figure 1 is a top plan view of a tee, constructed and arranged in accordance with the invention showing in conjunction therewith a golf ball in position to be played upon.

Figure 2 is a top plan view of the same.

Figure 3 is a side view of a tee, constructed and arranged in accordance with a further 20 modification of the invention showing in conjunction therewith a golf ball in position to be played upon.

Figure 4 is a top plan view of the same.

Figure 5 is a side view of a further modification 25 of the invention showing in conjunction therewith, a golf ball in position to be played upon.

Figure 6 is a top plan view of the same.

30

Description.

As seen in the drawings, tees when constructed and arranged in accordance with the present invention are preferably constructed of a single piece of wire having an 35 elongated stem 14 and a bracket arm 17 at one end of which is a coil or circular ring 15. The ring 15 may be closed or left open, as desired. It is properly disposed in a plane perpendicular to the stem 14. The 40 bracket arm 17 is usually disposed perpendicular to the stem 14 though this may be varied if desired, by bending the arm to a position inclined from the stem 14, but in all events, the ring 15 should be disposed 45 in a plane as stated perpendicular to the stem 14.

In practice, the tee is placed in position by forcing the end of the stem 14 into the ground sufficiently far to resist the tilting 50 strain imparted thereto by the weight of the golf ball when the same is placed in the ring 15 with the end of the bracket arm.

When now the person playing, strikes the ball, the tee offers little, if any, resistance 55 to the stroke and avoids the jump of the ball so often occasioned by the edge of the

seat formed in the mechanical tees of usual construction. This is avoided in the present invention by the tee swinging around the stem 14 as on a pivot. The swing referred 60 to has the effect of easing up the lifting effort for unseating the ball.

A further advantage in providing tees of the character mentioned which will swing or be carried by the force of the blow is that 65 the full force of the stroke is neither impeded or interfered with. The further advantages in the use of tees of the character mentioned is to be found in the fact that the player is not interfered with by any apprehension or other mental disturbance, the outcome of a feeling that he must avoid hitting the tee. If the tee is struck when constructed in accordance with the present invention, it is only swung around the stem 14 which 75 offers little or no resistance to the stroke.

A further advantage to be found in using the construction is that the tee is not lost by being driven from its service position into the high grass or other foliage surrounding the teeing ground.

In Figures 3 and 4, a modified form of the invention is shown, the modification consisting in providing an offset loop 18, the purpose of which is to furnish a rest for 85 the thumb to assist in pushing the stem 14 into the ground.

In Figures 5 and 6, another modification of the invention is disclosed, wherein the bracket arm is dispensed with, the stem 14 90 terminating or being immediately connected with the ring 15. It will be observed that while this form of the invention has an advantage in that the tees will back closer than the other forms, it will nevertheless, 95 not afford some of the advantages above referred to relating to the avoidance of the head of the club in play. It will, however, swing around the stem 14 in the manner above described though not with the same 100 facility.

It is obvious that while I have herein described the tee as being constructed from a single piece of wire, the arm 17 and ring 15 being formed integrally therewith may be 105 pivotally connected with the stem 14 without passing beyond the scope of the present invention.

Claims.

110

1. A golf tee formed of a single strip of wire bent to provide an elongated vertical

stem for insertion in the earth, the free end of said strip being extended in a horizontal plane at a right angle to said stem and formed at its terminal with an open centered ring to seat a golf ball, said strip being formed in the horizontal extension thereof intermediate said ring and stem with the lateral extension forming a pressure head for forcing said stem into the earth.

2. A golf tee formed of a single strip of wire looped at one end in an open centered ring to receive a golf ball thereon, said strip being extended from said ring in the plane of said ring and bent upon itself to provide a pressure head, said strip beyond said head being bent at a right angle to provide a stem for insertion in the earth.

GEORGE H. OLDRING.
